REFRIGERATOR

Thomas I. Potter, Buffalo, N. Y., assignor to
Refrigeration Patents Corporation, Buffalo,
N. Y., a corporation of New York

Application June 5, 1934, Serial No. 729,072
Renewed September 15, 1938

18 Claims. (Cl. 62—116)

The present application is a continuation in part of my copending application Serial No. 659,916, filed March 7, 1933, now abandoned. The invention relates to household refrigerators having plural food chambers, and more particularly to refrigerators of this type in which different temperatures and different hygroscopic conditions are maintained in the several chambers.

Heretofore, it has been customary to provide a separate door for each chamber of such a refrigerator. In contrast to this the present invention has for an object to provide a refrigerator in which a single door serves for a plurality of food chambers. An advantage of this construction is that it reduces cost of manufacture and makes for a very neat appearance. Furthermore, the lineal extent of door joint that must be protected against thermal leakage from the outside atmosphere is materially reduced.

Another object of the present invention is to provide a refrigerator in which the thickness of thermal insulation of the several chambers depends upon the temperatures to be maintained therein.

The heat insulation used in refrigerators is by no means a perfect bar to the flow of heat therethrough. Instead, it serves merely to impede the flow of heat, and consequently if the walls of the refrigerator are of the same thickness and of the same quality of insulation there will be a greater inflow of heat per unit of area into the colder chamber than into the warmer chamber because this inflow will depend upon the temperature head. Heretofore, it has generally been considered necessary to provide a maximum bar to the inflow of heat, the only limitations being those imposed by economy and bulkiness of the material. In contrast to this I reduce the insulation of one chamber with respect to that of the other so as to balance the heat flow into the heat chambers or so as to actually have a greater inflow of heat into the higher temperature chamber than into the lower temperature chamber. This feature is disclosed in U. S. Letters Patent to Bronaugh et al., 2,056,165, granted October 6, 1936, on an application Serial No. 516,032, filed February 16, 1931. The chambers are cooled by evaporators connected in series and a thermostatic switch located in the warmer chamber controls the heat pumping unit. Unless the insulation of the two chambers were properly balanced there would be a greater inflow of heat into the colder chamber and this

might warm up considerably before the warmer chamber was warmed sufficiently to actuate the thermostat. By providing a thinner insulation for the warmer chamber the latter will be warmed at the same rate as or more quickly than the colder chamber and the thermostat will be actuated to start the heat pumping unit and restore the temperatures in the two chambers to the desired differential. In said application the two chambers are provided with individual doors. I have found, however, that there is a distinct advantage in using a single door for the two chambers. Every time the door is opened heat is admitted into the two chambers. If the chambers are provided with individual doors and the colder temperature chamber were opened frequently, it might become unduly warm before the thermostat would operate in the other chamber to restore it to its desired cold temperature. If the thermostat were located in the colder chamber, frequent opening of the door of the warmer chamber would result in warming the latter chamber too much before the thermostat would operate. By having a single door for both chambers this unbalanced condition is obviated. Usually the warmer chamber is placed above the cold chamber and when the door is opened cold air spills out of the cold chamber and is replaced by cool but warmer air from the upper chamber. The air that flows out of the upper chamber is replaced by air from the outside atmosphere. Since the difference in temperature between the two chambers is usually less than that between the upper chamber and the outside atmosphere the effect of opening the door is to introduce more heat into the upper chamber than into the lower chamber, particularly as the upper chamber is the larger. In any case, the use of the single door results in introducing heat into both of the chambers every time the door is opened instead of into one chamber alone so that there is less disturbance of balance and no danger of having one chamber heated to an undesirable temperature before the thermostat will act to restore the differential.

A further and more specific object of the invention is to provide a door formed with a plurality of panels, one for each chamber, and with thermal insulation between the panels.

Another object of the invention is to provide means for effectively sealing one chamber from the other when the door is closed.

Still another object of the invention is to provide a double insulation for the closure means

of a chamber in which a low temperature is to be maintained.

Other objects and advantages of the invention will appear in the following description of a preferred embodiment and thereafter the novelty and scope of the invention will be pointed out in the claims.

In the accompanying drawing:

Figure 1 is a view in perspective of my improved plural-chambered refrigerator showing 10 the door open;

Fig. 2 is a fragmental view in vertical section taken in the plane 2—2 of Fig. 1 with the door closed;

Fig. 3 is a fragmental view in vertical section 15 taken on the line 3—3 of Fig. 3; and

Fig. 4 is a sectional view on an enlarged scale of a portion of Fig. 2.

In the drawing, I have used the reference numeral 10 to indicate a refrigerator cabinet provided with two food chambers. This cabinet is formed with a lower compartment 11 in which the refrigerating mechanism (indicated generally at 12) is housed. The compartment 11 is closed by a door 11a. The upper part of the cabinet comprises food-chambers 13 and 14, disposed one above the other. The upper of these chambers is intended to be kept at a temperature low enough to preserve food but well above the freezing point, while the lower of these chambers is maintained at a temperature in which water and foods may be quickly frozen.

The cabinet may be constructed in the well-known manner of an outer metallic shell 15 in which are placed tanks 16 and 17 of sheet metal or other suitable material to form the chambers 13 and 14 respectively. Suitable insulation 18 is filled between the tanks and the outer shell. This insulation is extended under the tank 14 and also between the two tanks to form an insulating partition 19 between the chambers. Since the lower chamber 14 is to be maintained at a much lower temperature than the upper chamber 13, the tank 17 is preferably somewhat narrower and shallower than the tank 16 so as to provide for greater thickness of insulation between tank 17 and the shell 15, as clearly indicated in Figs. 2 and 3. The tanks open at the front of the cabinet and are adapted to be closed by a single door 20. Hence a door frame is provided embracing both chambers. This frame flares outwardly and is faced with strips 21 of insulating material such, for instance, as Bakelite, connecting the shell and tanks.

The partition 19, as shown in Fig. 2, terminates flush with the inner edge of the door frame. The outer edge of the partition comprises a down-turned flange 23 of the bottom wall of tank 16 and an up-turned flange 24 of the top wall of the tank 17. However, these two flanges do not meet but are connected by a facing strip of insulation material 25. Thus, there can be no transfer of heat from the upper chamber to the lower chamber by way of the metallic walls of said chambers. A pair of gaskets 27 and 28 are located respectively at the upper and lower corners of the front edge of the partition 19. These gaskets are of a type well known in the art, consisting of rubber strips in tubular form and adapted to be flattened by the door when it is closed to seal the door joint. The gaskets are clamped in place by the facing strip 25. The upper gasket 27 terminates at each end of the partition but the lower one is extended around the entire door opening of the lower chamber 75

14, being clamped under the door frame strips 21.

The door 20 is hinged to the cabinet and following common practice, may be formed of a metal shell 29 filled with insulation material 30. 5 The door edges are bevelled to fit the flare of the door frame, and are faced with strips of insulation 31 adapted to fit against the strips 21 when the door is closed. It will be understood that there is a gap in the metal shell under the strips 31 to interrupt thermal conductivity. The outer face of the door is extended beyond the bevelled edges to form a bead 32 and within this bead is a gasket 33 adapted to bear against the face of the cabinet around the door frame when the door is closed.

The inner face of the door is formed with two panels 34 and 35 to close the chambers 13 and 14 respectively. The panels are separated by a recess in the shell of the door and there is a break in the metal shell in this recess which is closed by a strip 36 of insulation material. When the door is closed, as shown in Fig. 3, the gaskets 27 and 28 will prevent leakage of air around the front edge of the partition from one chamber to the other and the insulation strips 25 and 36 will interrupt thermal conductivity along the walls of the partition and door respectively.

The chamber 14 is shown as having a freezing shelf 40. This contains a coil of piping through which a refrigerant is circulated by the refrigerating plant 12. This shelf extends from side to side of the refrigerator and close to the upper wall of the chamber 14 but spaced sufficiently therefrom to permit of the insertion of ice trays and other receptacles in which desserts and the like are to be frozen.

In the upper part of the chamber 13 is located a non-frosting coil 41 which is connected in series with the freezing shelf by means of pipes 42 embedded in the rear wall of the cabinet. A suitable shield 43 conceals the coil 41. A thermostatic switch 45 is located at any suitable point in the chamber 13, to control the circuit 46 of an electric motor 47 which drives the refrigerating mechanism. This switch may be set to maintain the chamber 13 at a cool but non-freezing temperature, say 40 degrees Fahrenheit. Because of the series connection of elements 40 and 41 the chamber 14 will be cooled to a much lower temperature, say between zero and ten degrees Fahrenheit. This wide difference of temperature is maintained by the greater thickness of insulation in the walls of the lower and colder chamber than in those of the upper chamber, so that between operations of the heat pumping unit 12 the temperature gradient in the two chambers will be substantially alike, and when the door 20 is opened heat will be admitted to both chambers.

Since the coil 41 is of the non-frosting type a considerable moisture content may be maintained in this chamber so as to prevent desiccation of food. In the lower chamber, however, moisture will collect as frost on the freezing shelf and the atmosphere in this chamber will, therefore, be very dry. Such being the case it is desirable to prevent, as far as possible, not only the transfer of heat from the compartment 13 to the compartment 14 but also the transfer of moist air from one compartment to the other. The gaskets 27 and 28 prevent such circulation of air when the door is closed, and when the door is open cold air will spill out at the bottom of each chamber and some of the moist air from the upper chamber will enter the lower chambers. 70 Such slight transfer of moisture has not been

found to be of material consequence because usually there is more moisture in the warm air entering the top of chamber 13 than in the cool air which spills out at the bottom of said chamber.

I have found that without a break in the metal wall of the door 20 there will be a sufficient transfer of heat along the inner face of the door to produce a sheet of frost thereon opposite the lower part of chamber 13, thus reducing the moisture content of said chamber. However, this is entirely prevented by forming the inner face of the door with separate panels and forming a break in the metal path from one panel to the other. It will also be observed that the 15 partition 19 is provided with an upwardly projecting rim 48 which prevents any dripping from the upper chamber over the edge of the partition.

Instead of placing the thermostatic switch in the warmer chamber it may be placed in the lower chamber 14 so that the heat pumping unit would be controlled by variations of temperature in the colder chamber.

While I have described a preferred embodiment of my invention, I wish it to be understood that this is to be taken as illustrative and not limitative of my invention, and also that I reserve the right to make such variations in construction, and arrangement of parts as fall within the spirit and scope of the following claims.

I claim:

1. A household refrigerator comprising a cabinet formed with two cooling chambers thermally insulated from each other, a single door adapted to close both of the chambers and seal one chamber from communication with the other, and heat pumping means adapted to cool one of the chambers to a lower temperature than the other, said door comprising separate panels of heat conductive material for closing the respective chambers and means thermally insulating one panel from the other to prevent conductive exchange of heat through the panels from one chamber to the other.

2. A household refrigerator comprising a cabinet formed with two thermally insulated cooling chambers disposed one above the other, a single door adapted to close both of the chambers, heat pumping means adapted to cool the lower chamber to a lower temperature than the upper chamber, said door comprising thermally separated panels for closing the respective chambers, and a gasket of insulation material surrounding the door opening of the lower chamber and adapted to engage the lower panel when the door is closed.

3. A household refrigerator comprising a cabinet formed with a pair of cooling chambers thermally insulated from each other and separated from each other by a transverse partition extending from side to side of the cabinet, a single door adapted to close both of the chambers, a pair of gaskets of insulation material disposed respectively at the upper and lower edges of the partition and adapted to engage the door when the latter is closed, said gaskets providing therebetween a dead air space when the door is closed thermally separating one chamber from the other, the door and the partition being provided with strips of insulation material forming the front and rear walls of said dead air space and adapted to obstruct the passage of heat from one chamber to the other through the door or the partition, and refrigerating means adapted to cool

one of the chambers to a much lower temperature than the other, one of the gaskets being extended about the entire door opening of the cooler chamber.

5. A household refrigerator comprising a cabinet formed with a pair of cooling chambers thermally insulated from each other and separated from each other by a transverse partition extending from side to side of the cabinet, a single door adapted to close both of the chambers, a pair of gaskets of insulation material disposed respectively at the upper and lower edges of the partition and adapted to engage the door when the latter is closed, said gaskets providing therebetween a dead air space when the door is closed thermally separating one chamber from the other, the door and the partition being provided with strips of insulation material forming the front and rear walls of said dead air space and adapted to obstruct the passage of heat from one chamber to the other through the door or the partition, and refrigerating means for cooling the chambers, said refrigerating means being thermally balanced to maintain a sharp freezing temperature in one of the chambers and a temperature above the freezing point in the other chamber without exposing the latter to a frosting surface.

5. A refrigerator comprising a cabinet formed with two compartments and with heat insulation separating said compartments from each other and from the outside atmosphere, refrigerating means for abstracting heat from both of said compartments, the insulation of said compartments being adapted to offer a higher resistance to inflow of heat into one compartment than into the other, thermo-sensitive means in the latter compartment for controlling said refrigerating means, a single door for closing the openings of both of said compartments, means sealing the door about both said openings and additional means sealing the door about the opening of the compartment insulated to offer the higher resistance to inflow of heat.

45. 6. A refrigerator comprising a cabinet formed with a cooling compartment and a freezing compartment, thermally insulated from each other and from the outside atmosphere, refrigerating means for cooling the freezing compartment to a lower temperature than that of the cooling compartment, the thermal insulation of the compartments being so relatively proportioned as to offer a greater resistance to inflow of heat into the freezing compartment than into the cooling compartment, thermo-sensitive means for controlling the refrigerating means, said thermo-sensitive means being located in the compartment in which there is the greater normal inflow of heat, and a single door for closing the openings of both of said compartments.

7. A refrigerator comprising a cabinet formed with a cooling compartment and freezing compartment, thermally insulated from each other and from the outside atmosphere, refrigerating means for cooling the freezing compartment to a lower temperature than that of the cooling compartment, the thermal insulation of the compartments being so relatively proportioned as to offer a greater resistance to inflow of heat into the freezing compartment than into the cooling compartment, thermo-sensitive means for controlling the refrigerating means, said thermo-sensitive means being located in the compartment in which there is the greater normal inflow of heat, and a single door for closing the

openings of both of said compartments, and said compartment into which there is a greater normal inflow of heat being located above the other compartment.

8. A household refrigerator comprising a cabinet formed with a pair of thermally insulated chambers disposed one above the other, each chamber having a door opening, the cabinet being formed with a door frame embracing both of said openings, a door hinged to the cabinet and adapted to fit said door frame, said door having a pair of panels adapted to close said openings respectively, and thermally insulated from each other, a gasket of insulation material between said door and cabinet, another gasket of insulation material disposed between the door and the opening of the lower chamber and heat pumping means adapted to cool the lower chamber to lower temperature than that of the upper chamber.

9. A household refrigerator comprising a cabinet formed with two cooling chambers thermally insulated from each other, a single door adapted to close both of the chambers, heat pumping means adapted to cool one of the chambers to a lower temperature than the other, said door comprising separate panels for closing the respective chambers, a gasket of insulation material between the walls of the door opening of one of the chambers and the adjacent panel and insulation material separating one panel from the other to obstruct transfer of heat by way of the door from the warmer chamber to the cooler chamber.

10. A household refrigerator comprising a cabinet formed with a pair of cooling chambers thermally insulated from each other by a transverse partition extending from side to side of the cabinet, a single door adapted to close both of the chambers, a pair of gaskets of insulating material respectively disposed between the upper and lower edges of the partition and said door when the door is closed providing therebetween a dead air space thermally separating one chamber from the other, the door and partition being provided with strips of insulation material forming the front and rear walls of said dead air space and adapted to obstruct the passage of heat from the one chamber to the other through the door and partition and refrigerating means adapted to cool one of the chambers to a much lower temperature than the other.

11. A household refrigerator comprising a cabinet formed with a pair of cooling chambers thermally insulated from each other by a transverse partition extending from side to side of the cabinet, a single door adapted to close both of the chambers, a pair of gaskets of insulating material respectively disposed between the upper and lower edges of the partition and said door when the door is closed providing therebetween a dead air space thermally separating one chamber from the other, and refrigerating means adapted to cool one of the chambers to a much lower temperature than the other.

12. A household refrigerator comprising a cabinet formed with a pair of cooling chambers thermally insulated from each other by a transverse partition extending from side to side of the cabinet, a single door adapted to close both of the chambers, a pair of gaskets of insulation material disposed between the upper and lower edges of the partition and the door when the latter is closed, said gaskets providing therebetween a dead air space when the door is closed thermally separating one chamber from the other, the door

and partition being provided with strips of insulation material forming the front and rear walls of said dead air space and adapted to obstruct the passage of heat from one chamber to the other through the door and the partition, and refrigerating means for cooling the lower chamber to a much lower temperature than the upper chamber, the lower gasket being extended about the entire door opening of the lower chamber.

13. A household refrigerator comprising a cabinet provided with two cooling chambers insulated from each other, refrigerating means adapted to cool one of the chambers to a temperature below freezing and the other to a temperature above freezing without frosting, and a single door adapted to close both of the chambers and seal them from communication with each other, said door including means for preventing transfer of heat therethrough from the warmer to the cooler chamber.

14. A household refrigerator comprising a cabinet provided with two cooling chambers insulated from each other, each chamber being provided with a door opening, refrigerating means adapted to cool one of the chambers to a temperature below freezing and the other to a temperature above freezing without frosting, a single door for closing the openings of both of the chambers, insulation material between the door and cabinet and surrounding said openings for sealing said chambers from the outside atmosphere, and insulation material between the door and cabinet and surrounding the opening of one of said chambers for sealing said chambers from communication with each other.

15. Refrigerating apparatus including an insulated cabinet having separate freezing and food compartments, insulating means extending between the freezing and food compartments for insulating the compartments from each other, a common insulated refrigerator cabinet door providing access to both the freezing and food compartments, resilient sealing means extending from said insulating means into sealing contact with the common door when in the closed position for preventing the flow of air from one of the compartments to another, and a refrigerating system including refrigerant liquefying means and refrigerant evaporating means having separate portions in heat exchange relation with the freezing compartment and the food compartment for maintaining said compartments at different temperatures.

16. Refrigerating apparatus including an insulated cabinet having an insulated partition providing separate freezing and food compartments insulated from each other, a common refrigerator cabinet door providing access to both the freezing and food compartments, resilient sealing means cooperating with said partition and said door when in closed position for preventing the flow of air from one compartment into contact with the other compartment, and a refrigerating system including refrigerant liquefying means and refrigerant evaporating means having separate portions in heat exchange relation with the freezing compartment and the food compartment for maintaining said compartments at different temperatures.

17. A household refrigerator comprising a cabinet provided with two cooling chambers insulated from each other, each chamber being provided with a door opening, refrigerating means adapted to cool one of the chambers to a temperature below freezing and the other to a temperature

above freezing, a single door for closing the openings of both of said chambers, sealing means between the door and the cabinet and surrounding both of said openings for sealing said chambers from the outside atmosphere, and sealing means between the door and the cabinet for sealing said chambers from communication with each other.

18. A household refrigerator comprising a cabinet provided with separate tanks thermally in-

sulated from each other and from the outside atmosphere and constituting chambers to be maintained at different temperatures, a common door for closing the openings of said tanks, and sealing means between the door and the cabinet for sealing said chambers from communication with each other.

THOMAS I. POTTER.
